Attorney:

UNITED STATES PATENT OFFICE.

FREDERICK BERNARD CUMPSTON, OF BLOOMING GROVE, TEXAS,
ASSIGNOR OF ONE-THIRD TO T. W. SEWELL, ONE-THIRD TO
R. J. PAGE, AND ONE-THIRD TO M. G. YOUNG, OF BLOOMING
GROVE, TEXAS.

AUTOMATIC COTTON PRESS AND FEEDER.

No. 836,488.

Specification of Letters Patent.

Patented Nov. 20, 1906.

Application filed April 2, 1906. Serial No. 309,506.

To all whom it may concern:

Be it known that I, FREDERICK BERNARD CUMPSTON, a citizen of the United States, residing at Blooming Grove, in the county of Navarro and State of Texas, have invented certain new and useful Improvements in Automatic Cotton Presses and Feeders, of which the following is a specification.

This invention relates to an improvement in cotton-presses, and more particularly to that type of cotton-presses designed to be actuated by fluid-pressure.

The object of the present invention is the provision in a press of this character of means for automatically operating the throttle-valve to cause the descent of the piston when the press-box is filled with cotton and means for automatically reversing the throttle-valve when the plunger reaches its lowermost position.

A further object of the invention is the provision of automatic means for slowly actuating the throttle to cause the descent of the plunger and automatic means for quickly actuating the throttle to cause the ascent of the plunger.

A further object of the invention is the provision of means for automatically feeding the cotton into the press-box from the condenser.

Other objects of the invention will be apparent from the detailed description herein-after made when read in connection with the accompanying drawings, forming a part hereof, wherein a preferable embodiment of my invention is shown and wherein like letters of reference refer to similar parts in the several views.

In the drawings, Figure 1 is a side elevation of my improved cotton-press. Fig. 2 is a longitudinal section thereof. Fig. 3 is a top plan view of my improved press. Fig. 4 is a detail view of the mechanism for automatically throttling the movements of the throttle-valve, and Figs. 5 and 6 are detail views showing the arrangement of the throttle-valve with reference to the power-cylinder.

Referring now more particularly to the drawings, A designates a condenser, which may be of any suitable form and construction, and B designates the press-frame, within which is supported the press-box B', which may be of any suitable construction.

C designates a lint-chute which extends from the condenser into proximity to the top of the press-box B' and is adapted to convey the cotton from the condenser thereto. The edges of the lint-chute are provided with the grooves c, which extend longitudinally thereof.

D designates a bar which extends transversely across the lint-chute and is movable longitudinally thereof, the ends of the said bar fitting loosely in the grooves c in the side of the lint-chute C. The bar D is provided adjacent the end thereof with upwardly-extending ears d, in which is journaled a shaft d', the extremities of which are provided with the small cranked portions d². The shaft d' has secured thereto a plurality of downwardly-extending curved teeth d³, which are adapted to engage the cotton and force the same into the press-box when the bar D is moved downwardly in the groove c in the lint-chute.

E designates a shaft which extends transversely of the condenser A and is journaled in suitable bearings secured to the top thereof. The ends of the shaft E are provided with relatively large cranked portions e, which are connected by pitmen e' to the cranked portions d² of the shaft d'. The relative sizes of the cranked portions e and d² are such that the teeth d³, carried by the shaft d', will be held in engagement with the cotton in the lint-chute during the entire forward movement of the bar D, but will be raised out of engagement therewith during the rearward movement of said bar.

E' designates a drive-pulley secured to the shaft E.

F designates a drive-shaft which is positioned above the shaft E and is adapted to be constantly driven from any suitable source of power. One end of the shaft F is vertically movable in its bearing and carries a friction-wheel F', which is adapted to be moved into and out of frictional engagement with the pulley E', secured to the shaft E. The shaft F is moved vertically to bring the friction-wheel F', carried thereby, into and out of engagement with the pulley E' by a lever G, which engages said shaft and is fulcrumed on one of the bearings secured to the top of the condenser A. The forward end of said lever is adapted to occupy a position overlying the press-box for a purpose to be

hereinafter more particularly set forth. The lever G is preferably formed in two sections G' and G², which are hinged together adjacent their ends. A rod g is secured to the section G' adjacent the end thereof and beyond its pivotal connection with the section G² and extends upwardly through said section G². A spring g' is interposed between a nut secured to the upper end of the rod g and the upper surface of the section G² of the lever G. By this construction the friction-wheel F' will be held in yieldable engagement with the pulley E' when the free end of the lever G is elevated in a manner to be hereinafter more particularly set forth.

H designates the plunger of the press, which has secured to one edge thereof an upwardly-extending plate H', which is adapted to slide across the discharge end of the lint-chute and to constitute a cut-off to prevent the cotton therein from passing to the press-box except when the plunger H is in its elevated position. The cut-off plate H' is held against buckling or bending by a plurality of L-shaped braces H², the ends of which are secured, respectively, to the upper portion of said plate and to the opposite side of the plunger H.

I designates a steam-cylinder which is supported upon the top of the press-frame B. I' designates a piston adapted to reciprocate in said cylinder, and I² designates a piston-rod connecting said piston and the plunger H. Steam is admitted to the ends of the cylinder I through the pipes i and i'.

K designates a throttle-valve which may be of any suitable construction and which is designed to admit steam from the boiler to either the pipe i or the pipe i' to effect the raising and lowering of the plunger H.

Secured to one side of the press-frame B are a pair of separated guide-bars L, the inner edges of which are provided with grooves l for the reception of a plate L', which is slidably secured between said guides. The plate L' is connected by a rod l' with the throttle-valve K.

M designates a shaft journaled in suitable bearings secured to the frame and extending transversely of the guides L. The shaft M is adapted to be constantly driven from any suitable source of power and has secured thereto intermediate the guides L a disk M, which has secured to its opposite sides a large gear-wheel m and a small gear-wheel m'.

N designates an open frame which is pivotally secured to the plate L' and which embraces the shaft M. The upper and lower bars of the frame N are offset, so as to extend on opposite sides of the disk M', and the inner faces of said bars are provided with racks n and n', which are adapted to be respectively engaged by the gears m and m'. The upper bar of the frame N normally rests upon a stud o, secured to a lever O, which is

pivotaly mounted on an extension of one of the guides L, so that the racks n and n' are both held out of engagement with the gears m and m' of the disk M.

P designates an apron of angular cross-section, which is pivotally secured between bearings-blocks secured to the top of the press-frame near the edge thereof. The apron P extends transversely of the press-frame and in its normal position is adapted to underlie the plunger H.

P' designates an upwardly-extending arm secured to one of the pivots of the apron P. The arm P' is connected to the lever O by means of a link p. A spring O', secured to the extension of one of the guides L and bearing against the stud o, projecting from the lever O, serves to assist in maintaining the apron P in its normal position.

Q designates a shaft journaled in the press-frame and provided at one end with a cranked portion q, which is adapted to underlie the lower bar of the frame N. The cranked portion q may be provided with a friction-roller q', if desired. The opposite end of the shaft Q is provided with a cranked portion q² diametrically opposite to the cranked portion q, to which is secured an upwardly-extending rod R, which projects through an aperture in an arm h, which extends laterally from the top of the plate H'.

S designates a spring which encircles the rod R and the lower end of which is secured to a sleeve s, which is adapted to be secured to the rod R by means of a set-screw s'.

Having described the construction of my improved press, I will now set forth the operation thereof. Assuming that the plunger H is in its elevated position, the upper edge of the plate H having engaged the free end of the lever G and moved the same a sufficient amount to cause the friction-wheel F' to engage the friction-wheel E' it will be apparent that the bar D will be reciprocated and that cotton will be fed from the lint-chute into the press-box. When the press-box is filled, the incoming cotton will engage the apron P and force the same outwardly, which through the arm P' and link p will move the lever O a sufficient distance to withdraw the lug o thereof from out of engagement with the upper bar of the frame N.

The frame N will then drop by gravity, and the rack n' will be brought into engagement with the small gear m' of the constantly-rotating disk M, which will cause the throttle-valve K to be moved slowly to admit steam through the pipe i to the upper end of the cylinder, and thereby effect the downward movement of the plunger. The downward movement of the plunger will continue until the arm h, which extends laterally from the top of the plate H', contacts with the upper end of the spring S, which will cause the depression of the rod R, and consequently the

100

105

115

120

125

130

elevation of the cranked portion *q* of the shaft *Q*, which underlies the lower bar of the frame *N*. The elevation of the cranked portion *Q* will cause the rack-bar *n'* of the frame 5 *N* to be lifted out of engagement with the small gear *m'* and the rack-bar *n* to be brought into engagement with the large gear-wheel *m*, which will cause the throttle-valve *K* to be rapidly reversed to permit the admission of steam to the lower end of the cylinder *I* through the pipe *i'*, and thereby elevate the plunger. It will be obvious that by adjusting the position of the sleeve *s* on the rod *R* the reversal of the movement of the 10 plunger *H* can be effected at any desired time. As soon as the plunger starts its downward movement the weight of the lever *G* will raise the friction-wheel *F'* out of engagement with the pulley *E'*, and thereby 15 cause the feeding device to cease to operate.

I do not desire to limit myself to the precise form of construction shown in the drawings, and it is obvious that many minor changes might be made thereto without departing from the spirit and scope of the invention.

What I claim is—

1. In a device of the character described, a press-box, a plunger, means for intermittently raising and lowering said plunger, and automatic means for positively feeding material to the press-box controlled by the raising and lowering movement of said plunger. 30

2. In a device of the character described, a press-box, a plunger, means for intermittently raising and lowering said plunger, feeding instrumentalities for positively feeding a supply of material to the press-box, and means for automatically setting said feeding 35 instrumentalities into operation when the plunger is moved to its elevated position.

3. In a device of the character described, a press-box, a chute adapted to communicate therewith, a plunger, and a cut-off plate carried by said plunger, adapted to close the discharge end of said chute, except when said plunger is in its elevated position, a feeding device in said chute, and means for automatically actuating said feeding device when the plunger is moved to its elevated position. 45

4. In a device of the character described, a press-box, a chute adapted to communicate therewith, a reciprocating feeding device in said chute, a plunger, means for intermittently raising and lowering said plunger, and means for automatically actuating said feeding device when the plunger is in its raised position. 55

5. In a device of the character described, a press-box, a chute adapted to communicate therewith, a reciprocating feeding device in said chute, a plunger, a cut-off plate carried by said plunger, and closing the discharge end of said chute, except when said plunger 60 is in its elevated position, means for inter-

mittently raising and lowering said plunger, and means for automatically actuating said feeding device when the plunger is moved to its elevated position.

6. In a device of the character described, a press-box, a chute adapted to communicate therewith, a reciprocating feeding device in said chute, a normally stationary shaft for actuating said feeding device, a constantly-driven shaft, a plunger, means for raising and lowering said plunger, and means for automatically connecting the shaft of the feeding device with the constantly-rotating shaft when the plunger is moved to its elevated position. 75

7. In a device of the character described, a press-box, a chute adapted to communicate therewith, a feeding device in said chute, a plunger, means for raising and lowering said plunger, a shaft for actuating said feeding device, a friction-wheel carried by said shaft, a constantly-rotating shaft movably supported adjacent the actuating-shaft of the feeding mechanism and provided with a friction-wheel adapted to engage the friction-wheel thereon, and means for moving said constantly-rotating shaft to bring the friction-wheel carried thereby into engagement with the friction-wheel carried by the actuating-shaft of the feeding mechanism, when the 85 plunger is moved to its elevated position. 90

8. In a device of the character described, a press-box, a chute adapted to communicate therewith, a bar extending transversely of said chute and longitudinally movable therein, a shaft journaled in said bar and provided with cranked end portions, a plurality of teeth secured to said shaft, a drive-shaft having cranked end portions, and pitmen connecting the cranked portions of said shafts. 100

9. In a device of the character described, a press-box, a plunger, means for feeding material to the press-box, and means operable upon the filling of the press-box for effecting the lowering movement of the plunger. 110

10. In a device of the character described, a press-box, a plunger, means for feeding material to the press-box, means operable upon the filling of the press-box for automatically effecting the lowering of the plunger, and means operable by the lowering movement of the plunger for automatically effecting the reversal thereof. 115

11. In a device of the character described, a press-box, a plunger, a fluid-pressure cylinder, a piston therein, a connection between said piston and plunger, a valve controlling the admission of fluid to the opposite ends of said cylinder, automatic means for slowly actuating said cylinder to cause the lowering movement of said plunger, and automatic means for quickly actuating said valve to cause the raising movement of said plunger. 120

12. In a device of the character described, a press-box, a plunger, a fluid-pressure cylin- 125

der, a piston therein, a connection between said piston and cylinder, a valve controlling the admission of fluid to the opposite ends of said cylinder, means operable upon the filling of the press-box for actuating said valve to cause the lowering movement of said plunger, and means operable when said plunger reaches its lowermost position for actuating said valve to cause the raising movement of said plunger.

13. In a device of the character described, a press-box, a plunger, means for feeding material to the press-box, a member movably supported above the press-box and in the path of the incoming material, and means controlled by the movement of said member for automatically effecting the lowering of said plunger.

14. In a device of the character described, a press-box, a plunger, a fluid-pressure cylinder, a piston therein, a connection between said piston and plunger, a valve controlling the admission of fluid to the opposite end of said cylinder, means for feeding material to the press-box, a pivoted apron supported above the press-box and in the path of the incoming material, and means operable upon the movement of said apron for shifting said valve to effect the lowering of the plunger.

15. In a device of the character described, a press-box, a plunger, a fluid-pressure cylinder, a piston therein, a connection between said piston and cylinder, a valve controlling the admission of fluid to the opposite end of said cylinder, a constantly-rotating shaft having a large and small gear-wheel secured thereto, a reciprocating plate having racks adapted to engage with said large and small gear-wheels, a connection between said plate and said valve, means for normally supporting said plate so that the racks thereof will not engage with either of said gear-wheels, means automatically operable upon the filling of the press-box for causing one of the racks of said plate to engage with the small gear-wheel, and means automatically operable upon the lowering of the plunger for causing the other of said racks to engage with the large gear-wheel.

16. In a device of the character described, a press-box, a plunger, a fluid-pressure cylinder, a piston therein, a connection between said piston and cylinder, a valve controlling the admission of fluid to the opposite end of said cylinder, a reciprocating plate for actuating said valve, means for normally preventing the reciprocation of said plate, means operable upon the filling of the press-box for reciprocating said plate slowly in one direction, and means operable upon the lowering of the plunger for reciprocating said plate rapidly in the opposite direction.

17. In a device of the character described, a press-box, a plunger, means for feeding material to the press-box, means operable upon the filling of the press-box for automatically effecting the lowering of the plunger, and adjustable means for automatically effecting the return movement of the plunger.

18. In a device of the character described, a press-box, a plunger, means for elevating said plunger, means for automatically feeding material to the press-box when the plunger is elevated, and means operable upon the filling of the press-box for effecting the lowering movement of the plunger.

19. In a device of the character described, a press-box, a plunger, a feeding device for feeding material to the press-box, means for automatically actuating said feeding device when the plunger is moved to its elevated position, and means operable upon the filling of the press-box for automatically effecting the lowering movement of the plunger.

20. In a device of the character described, a press-box, a plunger, a feeding device for feeding material to the press-box, means for automatically actuating said feeder device when the plunger is moved to its elevated position, means operable upon the filling of the press-box for automatically effecting the lowering movement of the plunger, and means operable by the lowering movement of the plunger for automatically effecting the reversal thereof.

21. In a device of the character described, a press-box, a plunger, means adapted to feed material to the press-box, means for automatically actuating said feeding means when the plunger is moved to its elevated position, a member movably supported above the press-box and in the path of the incoming material, and means controlled by the movement of said member for automatically effecting the lowering of said plunger.

22. In a device of the character described, a press-box, a plunger, a fluid-pressure cylinder, a piston therein, a connection between said piston and cylinder, a valve controlling the admission of fluid to the opposite end of said cylinder, means operable upon the filling of the press-box for actuating said valve to effect the lowering of the plunger and means operable upon the lowering of the plunger for actuating said valve to effect the elevation of the plunger.

In testimony whereof I have signed my name to this specification in the presence of two subscribing witnesses.
